United States Patent Office

Des. 221,910

Patented Sept. 14, 1971

221,910

SURGICAL TABLE

Thomas Brendgord, Fairview, Pa., assignor to
American Sterilizer Company, Erie, Pa.

Filed Feb. 9, 1970, Ser. No. 21,339

Term of patent 14 years

Int. Cl. D24—02

U.S. Cl. D83—1

Fig. 1

Fig. 2

FIG. 1 is an isometric view of the surgical table showing one side and one end,

FIG. 2 is a view similar to FIG. 1 of the other side and other end of the table.

I claim:

The ornamental design for a surgical table, substantially as shown.
